(57) **CLAIM**

The ornamental design for a artificial turf cutting guide, as shown and described.

DESCRIPTION

FIG. 1 is a perspective view of a artificial turf cutting guide, showing my new design;

FIG. 2 is a top elevational view thereof;

FIG. 3 is a front elevational view thereof;

FIG. 4 is a rear side elevational view thereof;

FIG. 5 is a right side elevational view thereof; and,

FIG. 6 is a left side elevational view thereof.

The broken line showing of an interlocking element forms no part of the claimed design.
